DESIGN FOR A DRESS

Mary Geller, Chicago, Ill.

Application January 16, 1941, Serial No. 98,119

Term of patent 3½ years

To all whom it may concern:

Be it known that I, Mary Geller, citizen of the Union of the Soviet Socialist Republics, residing at 1350 Estes Avenue, Chicago, in the county of Cook and State of Illinois, have invented a new, original, and ornamental Design for a Dress, of which the following is a specification, reference being had to the accompanying drawing, forming part thereof.

I claim:

The ornamental design for a dress, substantially as shown.

MARY GELLER.
